UNITED STATES PATENT OFFICE.

GORDON W. BYRD, OF MENA, ARKANSAS.

TOBACCO-CAN.

1,277,846.

Specification of Letters Patent. Patented Sept. 3, 1918.

Application filed February 1, 1918. Serial No. 214,972.

To all whom it may concern:

Be it known that I, GORDON W. BYRD, a citizen of the United States, residing at Mena, in the county of Polk and State of

5 Arkansas, have invented new and useful Improvements in Tobacco-Cans, of which the following is a specification.

This invention relates to an improved tobacco can and match receptacle combined, 10 the object of the invention being to provide an improved form of tobacco can or other container which is provided at one end with a compartment for the reception of matches or the like for the convenience of the user.

15 With the above and other objects in view the invention consists in the construction, combination and arrangement of devices hereinafter described and claimed.

In the accompanying drawing:—

20 Figure 1 is a perspective view partly in section, of a tobacco can constructed to form also a match compartment, in accordance with my invention.

Figs. 2 and 3 are detailed sectional views 25 of the same.

My improved container which is here shown as a combined tobacco can and match box has a body 1 which is made from a single piece of sheet metal, preferably tin. The 30 blank from which the body of the container is formed is provided at one end of one side wall 2 with an extended portion or tongue 3. This extended portion or tongue is bent inwardly at said end of the container to form 35 a web 4 which bears against said wall and extends inwardly a suitable distance from said end of the container. The said web is then bent reversely as at 5 to form an inner web 6, which extends to about the center of 40 the web 4, and ~~said~~ tongue is then bent at right angles to said inner web to form a bot-

tom 7 which extends across the container, to the opposite side wall thereof, and which bottom is spaced from said end of the container.

45 A lid seat is hinged at said end of the container and to the last named wall and is adapted to close said end of the container, and in connection with the bottom 7 to form a compartment or pocket 8 for the reception 50 of matches or the like, so that the user of the tobacco can carry matches in the same receptacle, and thus greatly promote the convenience and utility of the container.

The opposite end of the container or can 55 is provided with the usual hinged lid 9 to close the same when desired.

My improved tobacco can is very cheap and simple, the provision of the match box or compartment thereof is a great convenience and is effected at a very inconsiderable cost, and is a convenience which is highly appreciated by tobacco users. The container is in practice also provided with a suitable 60 surface 10 on which the matches may be 65 ignited.

Having thus described my invention I claim:—

A receptacle of the class described having one side wall provided with a tongue, bent 70 inwardly to form a web which bears against said side wall, reversely bent to form an inner web, and at right angles to form a bottom, said bottom being spaced from said end of the container, and a lid on said end 75 of the container and coacting with the bottom to form a compartment in said end of the container for the reception of matches or the like.

In testimony whereof I affix my signature. 80

GORDON W. BYRD.
